[57] CLAIM

The ornamental design for a front surface of a desktop base station controller, as shown and described.

DESCRIPTION

FIG. 1 is a top perspective view of a front surface of a desktop base station controller showing my new design;

FIG. 2 is a front elevational view thereof;

FIG. 3 is a left side elevational view thereof;

FIG. 4 is a right side elevational view thereof; and,

FIG. 5 is a top plan view thereof.

The broken lines in FIGS. 1-5 are for illustrative purposes only and form no part of the claimed design.
